ASSORTING DEVICE

Angus F. Hanney, Norwood, Ohio, assignor to
The American Laundry Machinery Company,
Cincinnati, Ohio, a corporation of Ohio

Application September 8, 1930, Serial No. 480,423
Renewed February 13, 1934

10 Claims. (Cl. 40—19.5)

My invention relates to an assorting device and, particularly, to a device used in laundries for assorting or identifying customers' goods. The invention is especially adapted for identifying a plurality of pieces of goods contained in net bags as an entirety.

In the laundering operation, a plurality of pieces of goods are placed in a net bag which is labeled with an identifying marker and the bag is then passed through the various steps of the laundering operation in which net bags may be used with a number of other bags after which the bags are assorted according to their identifying markers. For instance, a single customer may send in a bundle of laundry work containing wool goods, white goods, colored goods, starched goods, and silk goods, etc. Therefore, for that customer's work there will be at least five bundles bearing like identifying markers. So that the bundles containing goods belonging to one customer may be properly assorted, it is desirable to provide an absolute check on the operator so that there will be no mixing or loss of bundles. Previous assorting has been done by placing nets bearing like numbered tags or checks in one place, as on a hook or bar but this gives rise to the possibility of incorrect reading of identification markers. Furthermore, there is the possibility that the assorter may take the easiest way of attaching the nets to a hook or bar by sliding the loops of the safety pins by means of which the identification markers are attached to the nets over the hook or bar and thus avoid the check against error which said markers and bar are intended to provide by their cooperating wards and notches.

Further, previous identifying systems employed in the identification of laundry work have not been of a character such that a sufficient number of different markers can be provided for handling the normal load of a commercial laundry. Such limitation in markers has been due to the warding arrangement used between the markers and racks or the like, the arrangement being such that a tag or marker itself could be reversed or inverted and thus be placed on a bar or rack other than that for which it was originally intended.

The objects of my invention are to provide an assorting device for laundries and particularly one adapted for use with identifying markers as used on net bags containing a plurality of pieces of a single customer's goods, whereby the assortment will be positively checked and the possibility of bags belonging to another group being coming mixed with the customer's goods elimi-

nated; and to provide a means whereby only like identification markers may be used in conjunction with a single bar or support.

Various other objects and advantageous features will appear from the following description of the invention and one embodiment thereof is illustrated in the accompanying drawing wherein similar characters of reference designate corresponding parts, and wherein:

Fig. 1 is a side view of an assorting device embodying my invention; Fig. 2 is a plan view thereof; Fig. 3 is a cross-sectional view thereof taken on the line 3—3 of Fig. 1; and Fig. 4 is a perspective view of an identifying check or marker used in conjunction with and forming a part of my invention.

Referring to the drawing, 1 represents a suitable identifying marker or tag adapted to be removably connected to a single piece of laundry work or to a net bag of such work by a safety pin 2, said pin being connected to the tag by means of a ring 3. In accordance with my invention, the tag 1 is provided with a suitable perforation 4 adapted to fit loosely over a smooth bar 5 which has an integral guard-supporting bar 6 spaced a short distance thereabove in parallel relation therewith. The two bars 5 and 6 are secured in any convenient manner to a wall or standard 7, such as by means of a bayonet slot 8 cooperating with a pin 9 in a suitable bracket 10 secured to said wall or standard.

The free end of the bar 6 carries a box-like guard or shield 11 having an open rear end and a bottom wall provided with a T-shaped slot 12. That portion of the slot 12 corresponding to the head of the T lies in a plane normal to that of the bar 5 and is provided with a plurality of notches 13 that may be disposed in any manner and form a combination, and the tag 1 is provided with a plurality of protuberances 14 on each side face thereof, there being one protuberance corresponding to each notch 13 in the guard or shield 11 so that the relatively thin and substantially flat tag may be passed edgewise upwardly through the head portion of the T-shaped slot 12. It will be noted that the outermost end of the bar 5 terminates within the box-like guard or shield 11 which forms a housing for that end.

In the operation of this assorting system, it will be noted that the portion of the slot 12 corresponding to the stem of the T-shaped slot is so narrow that a vertically disposed tag 1 can not be moved laterally therethrough in the direction of its transverse axis and the outermost end of the bar 5 is so close to the front end wall of

the guard or shield 11 as to further prevent such lateral movement of the tag through the slot. Thus, the tag 1 must be vertically disposed and passed edgewise upwardly through the head portion of the T-shaped slot 12 until the body portion of the tag is within the guard or shield 11, with its top edge engaging the bottom of bar 6. The tag is then moved laterally rearward until the receiving end of the bar 5 enters the centrally disposed slot 4 in the tag after which the tag will slide downwardly by gravity on the downwardly inclined bar 5 as shown in Fig. 1, with the part of the tag or identifying member that is outside of the shield moving through the stem of the T-shaped slot 12 until it comes to rest against the bracket 10 or against a tag that has previously been disposed on the bar. The tags may be removed from the bar 5 by reversing the order or procedure just described.

With this construction it will be seen that tags may be retained in properly assorted sets and after having been attached to laundry work will provide a means for insuring correct assorting of the laundry work into proper groups. To conveniently identify the individual tags of a group of like tags, both so that a group may be properly assorted and so that the combination of tag and bar may be readily apparent, each tag or check preferably has an identifying figure stamped thereon as is indicated at 15 while each guard or shield 11 is provided with a corresponding figure as indicated at 16. Further, there will always be a plurality of checks and different combinations of checks and bars inasmuch as the use of protuberances on the tags and the guard or shield 11 which necessitates that the tag must be in one position before it may be moved into cooperative relation with the bar provides such a warding arrangement that an unlimited number of different warding combinations may be used without danger of placing a tag or marker on the wrong bar. For example, slots 13 and protuberances 14 may have an unlimited number of positions and may vary widely as to number, etc.

45 What I claim is:

1. An assorting apparatus for laundry identifying members, comprising a housing having an open end, and a bar adapted to receive a plurality of identifying members, said bar having an identifying member receiving end projecting through the open end of said housing and arranged to coat with a wall of the housing to define an identifying member receiving location but slightly thicker than such members and from which they may be moved onto said bar, and warded means in said housing providing an entrance for said identifying members into such location, the warded means being adapted to coat with wardings on the identifying members whereby to limit such members assembled with said bar to like members only.

2. An assorting apparatus for laundry identifying members, comprising a housing having an open end, and a bar adapted to receive a plurality of identifying members, said bar having an identifying member receiving end projecting through the open end of said housing and arranged to coat with a wall of the housing to define an identifying member receiving location but slightly thicker than such members and from which they may be moved onto said bar, and warded means in said housing providing an entrance for the bar receiving portion only of said identifying members into such location, the remainder of each of said identifying members being outside of said

housing, said warded means being adapted to coat with wardings on the identifying members whereby to limit members assembled with said bar to like members only, said housing being provided with a slot whereby said identifying members may move through said slot and along said bar without interference between said housing and the part thereof disposed outside of said housing.

3. An assorting device for laundry identifying members, said device comprising an elongated support on which the body portions of like members are adapted to be removably mounted, and means associated with the receiving end portion of said support for limiting the mounting thereon to like members only, said means being provided with a special shaped gateway edgewise through which the body portions of such like members must pass before they can be mounted on said support, the body portions of each of said like members having a cross-sectional shape corresponding to the shape of said gateway.

4. An assorting device for laundry identifying members, said device comprising an elongated support on which the body portions of like members are adapted to be removably mounted, and means associated with the receiving end portion of said support for limiting the mounting thereon to like members only, said means being provided with a special shaped gateway edgewise through which the body portions of such like members must pass before they can be mounted on said support, the body portion of each of said like members having a cross-sectional shape corresponding to the shape of said gateway.

5. An assorting device for laundry identifying members, said device comprising an elongated support on which the body portions of like members are adapted to be removably mounted, and means associated with the receiving end portion of said support for limiting the mounting thereon to like members only, said means being provided with a special shaped gateway edgewise through which the body portions of such like members must pass before they can be mounted on said support, the body portion of each of said like members having a cross-sectional shape corresponding to the shape of said gateway, the plane of said gateway being normal to that of said support.

6. An assorting device for laundry identifying members, said device comprising an elongated support on which the body portions of like members are adapted to be removably mounted, and means enclosing the receiving end portion of said support for limiting the mounting thereon to like members only, said means being provided with a special shaped gateway edgewise through which the body portions of such like members must pass before they can be mounted on said support, the body portion of each of said like members having a cross-sectional shape corresponding to the shape of said gateway.

7. An assorting device for laundry identifying members, said device comprising an elongated support on which the body portions of like members are adapted to be removably mounted, and means associated with the receiving end portion of said support for limiting the mounting thereon to like members only, said means being provided with a special shaped gateway edgewise through which the body portions of such like members must pass before they can be mounted on said support, the body portion of each of said

like members having a cross-sectional shape corresponding to the shape of said gateway, said gateway and a side face of the body portion of each of said like members having cooperating 5 projections and projection-receiving notches.

8. An assorting device for laundry identifying members, said device comprising an elongated support on which the body portions of like members are adapted to be removably mounted, said support being inclined to the horizontal so that such like members mounted on the receiving end portion thereof will slide by gravity down along said bar, and means associated with the receiving end portion of said support for limiting the 10 mounting thereon to like members only, said means being provided with a special shaped gateway edgewise through which the body portions of such like members must pass before they can be mounted on said support, the body portion of 15 each of said like members having a cross-sectional shape corresponding to the shape of said gateway.

9. An assorting device for laundry identifying members, comprising a bar on which the body 20 portions of like members are adapted to be removably mounted, and means associated with the receiving end portion of said bar for limiting the mounting thereon to like members only, said means being provided with a special shaped gate-

way edgewise through which the body portions of such like members must pass before they can be positioned in front of said bar for subsequent mounting thereon, the body portion of each of said like members being provided with an aperture 25 to receive said bar and having a cross-sectional shape corresponding to the shape of said gateway.

10. An assorting device for laundry identifying members, comprising an elongated support on which the body portions of like members are adapted to be removably mounted, means arranged below the receiving end portion of said support for limiting the mounting thereon to like members only, said means being provided with a special shaped gateway edgewise through which the body portions of such like members must pass before they can be positioned in front of the receiving end portion of said support for mounting thereon, and an abutment arranged 30 above the receiving end portion of said support for limiting the upward movement of said members, by engagement therewith, to insure proper positioning of the body portions thereof in front of said support for subsequent mounting thereon, the body portion of each of said like members having a cross-sectional shape corresponding to the shape of said gateway.
